CLAIM

The ornamental design for a isometric exerciser, as shown and described.

DESCRIPTION

FIG. 1 is a perspective view of an isometric exerciser showing my new design;
FIG. 2 is a frontal elevational view thereof;
FIG. 3 is a bottom plan view thereof;
FIG. 4 is a top view thereof;
FIG. 5 is a rear elevational view thereof; and,
FIG. 6 is a left side elevational view thereof, the side opposite being a mirror image.
